(57) **CLAIM**

The ornamental design for a vehicle component, as shown
and described.

DESCRIPTION

FIG. 1 is a perspective view of a vehicle component showing
my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top view thereof;

FIG. 7 is a bottom view thereof;

FIG. 8 is a left side elevation view thereof with shading; and,

FIG. 9 is a perspective view thereof with shading.

The broken lines in the drawings illustrate portions of the
vehicle component that form no part of the claimed design.

1 Claim, 8 Drawing Sheets
